UNITED STATES PATENT OFFICE

VICTOR T. SCHMITT, OF CHICAGO, ILLINOIS, ASSIGNOR TO HINCKLEY & SCHMITT, OF CHICAGO, ILLINOIS, A CORPORATION OF ILLINOIS

DESIGN FOR A WATER COOLER

Application filed April 15, 1929. Serial No. 30,894. Term of patent 3½ years.

To all whom it may concern:

Be it known that I, VICTOR T. SCHMITT, a citizen of the United States, residing at Chicago, Cook County, Illinois, have invented a new, original, and ornamental Design for Water Coolers, of which the following is a specification, reference being had to the accompanying drawing, forming part thereof, showing my new design, which constitutes a relatively tall and slim cabinet having an inverted water bottle on the top thereof, a faucet extending from one face of the cabinet and below the top thereof, a substantially semi-cylindrical drip pan below the faucet, and perforations below the drip pan, and flush hand hole covers in the top and one side of said cabinet.

I claim:

The ornamental design for a water cooler as shown and described.

VICTOR T. SCHMITT.
